DESIGN FOR A SWIMMING PROPELLER

Harold L. Messinger, Los Angeles, Calif., assignor
of one-half to Lawrence P. Romano, Los
Angeles, Calif.

Application October 24, 1942, Serial No. 108,605

Term of patent 14 years

To all whom it may concern:

Be it known that I, Harold L. Messinger, a citizen of the United States, residing at 1319 Maple Avenue, Los Angeles, California, have invented a new, original, and ornamental Design for a Swimming Propeller, of which the following is a specification, reference being had to the accompanying drawing, forming part thereof.

Referring to the drawing:

Figure 1 is a perspective view of a swimming propeller, showing my new design;

Figure 2 is a top plan view of the device shown in Figure 1; and,

Figure 3 is a side elevation of the device.

I claim:

The ornamental design for a swimming propeller, as shown.

HAROLD L. MESSINGER.
